UNITED STATES PATENT OFFICE.

HOWARD E. CARLSON, OF MINNEAPOLIS, MINNESOTA.

RADIOCABINET.

Application filed May 8, 1924. Serial No. 711,839.

To all whom it may concern:

Be it known that I, HOWARD E. CARLSON, a citizen of the United States, residing at Minneapolis, in the county of Hennepin and State of Minnesota, have invented certain new and useful Improvements in Radio-cabinets; and I do hereby declare the following to be a full, clear, and exact description of the invention, such as will enable others skilled in the art to which it appertains to make and use the same.

This invention relates to radio apparatus and particularly to radio cabinets designed to enclose as much of the apparatus as possible without sacrificing the efficiency of the radio set.

The loud speaker horn and the aerial have been the most cumbersome and unsightly of the apparatus used in radio sets and have hitherto taken up considerable space in a room, as well as considerably marring the decorative appearance of the same.

It is the main object of this invention to provide a radio cabinet in which a rotatable loop aerial and loud speaker horn, as well as all other pieces of apparatus necessary in a receiving set, may be disposed, and permitting an aerial to be used of approximately the height and width of the inside of the cabinet.

It is a more specific object in such a cabinet to provide a loop aerial, which will revolve about the loud speaker horn and other pieces of radio apparatus mounted within the cabinet.

A further object of the invention is to connectedly mount all of the apparatus of the radio set to a removable panel, so that the entire set may be removed from the cabinet by lifting out the panel.

To these ends, generally speaking, the invention consists of the novel devices and combinations of devices hereinafter described and set forth in the claims.

The invention is illustrated in the accompanying drawings, in which like notations refer to similar parts throughout the several views, and in which,

Fig. 1 is a vertical section of the preferred form of the invention, with the movable position of one of the parts illustrated in dotted lines;

Fig. 2 is a fragmentary cross section taken on the line 2-2 of Fig. 1, with the moved position of some parts being indicated in dotted lines;

Fig. 3 is an enlarged fragmentary vertical section taken on the line 3-3 of Fig. 1;

Fig. 4 is a plan view of a modified form of the invention, the top panel of the cabinet being removed; and

Fig. 5 is an enlarged fragmentary vertical section of the modified form illustrated in Fig. 4, showing the operating mechanism of the revoluble loop aerial employed therein.

In the preferred form of the invention, illustrated in Figs. 1, 2 and 3, a closed cabinet 6 is provided in which the entire radio set is disposed, including the aerial and loud speaker horn. This cabinet has preferably a lid 6^a hinged to its top and pairs of horizontally swinging doors 7 and 7^a at its front and rear sides, respectively. A flange 8 extends around the four sides of the top of the cabinet and a panel 9 fits into the recess within the flange and closes the top of the cabinet, being supported by small blocks 10 secured to the inner four corners of the cabinet at the top thereof.

Oppositely disposed handles 9^a are secured to the top of panel 9 by which the panel may be inserted or removed from the cabinet. A depending journal member 11, preferably in the form of a flanged sleeve, is secured to the under side of the panel 9 centrally thereof. A flanged stud 12 is secured to the bottom of the cabinet in vertical alignment with journal member 11 and projecting upwardly towards the same. A flanged cap 13, forming a second journal member, is adapted to

removably be seated over the stud 12 and be supported by the same. A loop aerial is provided of approximately the height and width of the inside of the cabinet having a rectangular framework 14 equipped at its four corners with bridges 14^a normal to the plane of the frame 14 around which the usual continuous strands of wire 14^a are wound. The frame 14 is equipped at top and bottom with a pair of vertically aligned hubs 15 and 16, which are adapted to be mounted about the journal members 11 and 13, respectively, adjacent the top and bottom of the cabinet, thus permitting rotation of the aerial. The bridges 14^a are segmentally shaped along their outer edges to conform to the radius of revolution of the aerial, thus economizing space in the cabinet.

The hubs 15 and 16 are constructed of insulating material, such as "bakelite" or hard rubber. A supporting ring 17 is prefer-

80

100

105

110

ably threaded to the end of journal member 11 outside of the hub 15 and a relatively large supporting plate 18 is rigidly secured to said ring by small bolts 17^a. A second 5 ring 19 is threaded to the lower end of the journal member 13 below the hub 16 of the aerial, thus securing the aerial to the panel 9 with freedom for revolution. A second supporting plate 20 is secured to the top 10 flange of the cap or journal member 13 and is adapted to support the A and B batteries 21 and 22 used in the radio set. A loud speaker horn 23 is also mounted within the cabinet with its smaller end and loud 15 speaking unit disposed within the journal member 11 and secured to the bottom of the panel 9, preferably in alignment with the journal members 11 and 13. The various other pieces of radio apparatus are 20 mounted on the bottom of plate 18, such as the condensers 24 and 25, transformer 26, inductance coil 27, amplifying tube 28, and detector 29.

The regulation of the condensers 24 and 25 is provided for in the usual manner by means of the dials 30 on the top of panel 9, in which small shafts 31 are pivotally mounted having at their top ends dial knobs 32 and at their bottom ends small pinions 33, which engage with the regulating gears 34 of the condensers. The revolution of the loop aerial is controlled by a third dial knob 35 pivotally mounted in the dial plate 36 and carrying the shaft 37 with its lower 35 end equipped with the pinion 38. Pinion 38 engages with a gear ring 39 secured about the top hub 15 of the aerial. Since the aerial is revoluble about the remaining apparatus of the set, it is important that efficient electrical connections be made from the aerial to one of the condensers 24, which connections are provided for in the following manner.

A pair of spaced conducting rings 40 are 45 secured about the outer side of the hub 15 to which the two respective ends of the strands wound about the frame of the aerial 14 are connected. One end of the strands is secured to the electrical connection member 41 on the outside of the hub 15 and the other end of the strands passes within the insulated hub 15 and is secured to a countersunk electrical connection 42 on the inner side of the hub 15. A pair of spring brushes 50 55 43, secured to electrical connection members 44 of the condensers, are adapted to contact the rings 40, thus permitting the condenser 24 to span the electrical current passed through the strands of the aerial. 60 The radio set preferably used is of the ungrounded type used extensively today and the remaining pieces of radio apparatus, hitherto referred to, are connected together and with the batteries in the usual standard 65 manner. The loud speaker horn 23 has its

flared end disposed directly behind the front doors 7 of the cabinet, so that the sound may be transmitted to the outside of the cabinet when the doors are open. The back doors 7^a permit the operator to adjust or repair the 70 apparatus within the cabinet and also permit the batteries to be replaced. Since the journal member 11 is mounted to the under side of the removable panel 9 and supports the upper hub 15 of the aerial as well as 75 the plate 18 with the several pieces of apparatus secured to its under side, and since the lower end of the aerial supports the removable cap or journal member 13 with the plate 20 secured thereto, it is obvious that 80 the entire radio set and apparatus may be removed from the cabinet by revolving the aerial to a position on the diagonal of the bottom of the cabinet, indicated by dotted lines in Fig. 2, and lifting up on the panel 9 85 by means of the handle members 9^a. This structure thus permits the entire radio set to be taken out for repair or replacement of parts.

In order that a loud speaker horn, of 90 relatively large size, may be employed, a special horn is provided having its vertical sides segmentally cut away along a radius slightly smaller than that of the radius of the loop aerial, to permit the aerial to 95 revolve about the same without interference therewith.

The hub members 15 and 16 of the loop aerial are each equipped at their sides with a pair of horizontally aligned spacing members 45 extending perpendicularly to the frame 14 of the aerial. These spacing members hold the strands 14^a in spaced relation and divide and guide them around the hubs 15 and 16, so that the aerial may be 105 revolved without interference therewith.

The top of the panel 9 forms a dial face or operating board for the set, when the hinged cover 6^a is swung open and, by manipulating the different dial knobs in the 110 proper manner, the set may be tuned in and operated. By means of the dial knob 35, the aerial may be revolved to most effectively receive the Hertzian waves broadcasted. The entire radio set, exclusive of the aerial, 115 including the loud speaker horn, is mounted within the figure generated by the revolution of the aerial within the cabinet. Due to this structure, a loop aerial of approximately the inside width and height of the 120 cabinet may be employed. The unsightly and cumbersome aerial and loud speaker horn are thus completely hidden from view in a radio cabinet of the usual size, without impairing the efficiency of the receiving 125 apparatus.

The modified form of the invention, illustrated in Figs. 4 and 5, is similar in principle to the preferred form, but varies considerably in structure and arrangement 130

of parts. In Fig. 4, the cabinet is indicated by the numeral 46, having its top removed in which the A and B batteries of the set 47 and 48 are housed, preferably being 5 located in the two adjacent corners of the rear side of the cabinet 46. A loud speaker horn 49 has its smaller end and speaking unit secured to the inner side of the front wall of cabinet 46 adjacent one end thereof 10 and its flared end extends and communicates with an opening 50 in the front wall of the cabinet at the other end thereof. The radio set proper, including the several 15 pieces of apparatus, such as condensers, induction coil and amplifier, detector and transformer, is housed in the box 51 also secured to the inner side of the front wall of the cabinet, preferably midway between its top and bottom and between the loud 20 speaker unit and the flaring end of the speaker horn. The control dials 52 with the dial knobs extend at the outer side of the front wall of the cabinet, where they may be regulated. One side of the loop 25 aerial 53 of this modified form is pivotally mounted at top and bottom, best shown in Fig. 5, having a lower trunnion 54 journaled in a pivot member 55 mounted on the bottom of cabinet 46 and has an extended 30 trunnion 56 journaled in the top panel 57 of the cabinet and extending therethrough and terminating in the dial knob 58 on the outer side of panel 57. Revolution of the 35 aerial 53 is thus controlled by the knob 58 and the aerial may be revolved about the loud speaker horn and radio apparatus in the box 51, as illustrated by the dotted lines in Fig. 4.

In this modified form, as in the preferred 40 form, the loud speaker horn and radio apparatus is entirely within the figure generated by the revolution of the loop aerial and the entire radio set, including these devices, is disposed within the cabinet.

45 Actual usage has shown the invention to be successful for the purposes intended and to receive radio messages efficiently.

It is to be understood that various changes in the form, details and arrangement of 50 parts may be made without departing from the scope of the invention.

What I claim is:

1. In a radio set, a stationary frame, a coil 55 pivoted within said frame and means for mounting a plurality of pieces of apparatus within the figure generated by the revolution of said coil.

2. In a radio set, a stationary frame, a 60 loud speaker horn secured to one side of said frame and extending therewithin, and a loop aerial pivotally mounted within said frame and adapted to be revolved about said horn.

3. In a radio set, a stationary cabinet, a 65 loop aerial pivotally mounted within said cabinet, and means supported from said cab-

inet for mounting a plurality of pieces of radio apparatus within the figure generated by the revolution of said aerial within said cabinet.

4. In a radio set, a stationary cabinet having a pivot member supported from one of its sides, a loop aerial mounted within said cabinet having a co-operating pivot member pivotally engaging said first mentioned pivot member, and apparatus mounting means secured to said first mentioned pivot member and disposed within the figure generated by the revolution of said aerial. 70

5. In a radio set, a closed cabinet, a loop aerial mounted for revolution therein, a 80 plurality of pieces of radio apparatus mounted in said cabinet enclosed within the figure generated by the revolution of said aerial, and means disposed outside of said cabinet for revolving said aerial. 85

6. In a radio set, a closed cabinet having therein a pair of oppositely disposed pivot members, a loop aerial mounted on said pivot members for revolution within said cabinet, and means secured to the ends of 90 said pivot members for mounting a plurality of pieces of radio apparatus supported from the ends of said pivot members within the figure generated by the revolution of said aerial. 95

7. In a radio set, a closed cabinet having a pair of aligned pivot members projecting therein from opposite sides, a loop aerial provided at two of its opposite ends with 100 hubs mounted about said pivot members to permit said aerial to be revolved within said cabinet, supporting plates secured to the extremities of said pivot members outside of said aerial hubs, and a plurality of pieces of radio apparatus mounted on said plates within the figure generated by the revolution of said aerial, means for revolving said aerial. 105

8. In a radio set, a stationary cabinet, oppositely aligned inwardly projecting sleeves secured on opposite sides of said cabinet, a loop aerial mounted for revolution within said cabinet and having hub portions pivotally mounted on said sleeves, and a loud speaker horn having its smaller end secured and housed within one of said sleeves and wholly disposed within the figure generated by the revolution of said loop aerial. 110

9. In a radio set, a stationary cabinet, a 115 pair of oppositely aligned inwardly projecting sleeves secured to opposite sides of said cabinet, a loop aerial disposed within said cabinet having hub portions pivotally mounted on said sleeves and carrying a plurality of strands, and means on the opposite sides of the hub portions of said aerial for dividing said strands and guiding the same about said hub portions.

10. In a radio set, a stationary cabinet 120 comprising a main box-like structure and

- a removable cover panel therefor, an inwardly projecting pivot member secured to said cover panel; a loop aerial pivotally mounted on said pivot member and adapted to revolve within said cabinet and means secured to the end of said pivot member for mounting radio apparatus within the figure generated by said aerial, whereby said aerial and apparatus may be removed from said cabinet when said panel is lifted therefrom.
11. In a radio set, a closed cabinet, a loop aerial mounted for revolution therein comprising a rectangular shaped framework having at its four corners bridges about which the antenna strands are wound, said

bridges being normal to the plane enclosed by the frame and being of segmental shape to conform with the radius of revolution of the aerial.

12. In a radio set, a stationary frame, a loop aerial mounted to revolve within said frame and a loud speaker horn secured to said frame and disposed within the figure generated by the revolution of said aerial, said horn having two of its opposite sides segmentally cut to conform to the radius of revolution of said aerial.

In testimony whereof I affix my signature.

HOWARD E. CARLSON.
